CHARLES E. SMITH, OF NEW YORK, N. Y., ASSIGNOR TO REMINGTON TYPEWRITER COMPANY, OF ILION, NEW YORK, A CORPORATION OF NEW YORK.

TYPE-WRITING MACHINE.

1,154,344.

Specification of Letters Patent. Patented Sept. 21, 1915.

Application filed May 4, 1915. Serial No. 25,675.

To all whom it may concern:

Be it known that I, CHARLES E. SMITH, citizen of the United States, and resident of the borough of Brooklyn, city of New York, 3 in the county of Kings and State of New York, have invented certain new and useful Improvements in Type-Writing Machines, of which the following is a specification.

My invention relates to typewriting machines and more particularly to tabulating mechanism.

The main object of my invention, generally stated, is to provide comparatively simple tabulator mechanism with the aid of 15 which any desired column, or any desired denominational position within the desired column, may be readily selected by a single run of the carriage to the point of arrest, or in which denominational selection in successive columns may be effected.

A further object of my invention is to provide means of the character specified which may be readily embodied in typewriting machines equipped with tabulator mechanism 25 now employed on the market, and without modifying, or materially modifying, the structural features of such machines and tabulator mechanisms as they now exist.

To the above and other ends which will 30 hereinafter appear, my invention consists of the features of construction, arrangements of parts and combinations of devices set forth in the following description and particularly pointed out in the appended claims.

35 In the accompanying drawings wherein like reference numerals indicate corresponding parts of the different views, Figure 1 is a vertical fore and aft sectional view of one form of typewriting machines embodying 40 my invention, the section being taken on the line $x-x$ of Fig. 4 and looking in the direction of the arrows at said line. Fig. 2 is a detail fragmentary perspective view of the column stop bar and some of the associated 45 parts. Fig. 3 is a transverse sectional view of the same, the section being taken on the line $y-y$ of Fig. 2 and looking in the direction of the arrow at said line. Fig. 4 is a fragmentary plan view of the machine with 50 parts broken away and omitted. Fig. 5 is a skeleton view in side elevation of the tabulator mechanism, the view illustrating the parts in working positions. Fig. 6 is a detail diagrammatic perspective view of the 55 arresting means for the tabulator actuating

devices, and the means by which said members are controlled, the arresting bars being shown separated to better illustrate the construction. Fig. 7 is a transverse vertical sectional view showing these same members 60 and some of the associated parts, the view being taken on the line $z-z$ of Fig. 1 and looking in the direction of the arrow at said line.

In the various views I have illustrated 65 only so much of the typewriting machine as may be necessary to arrive at an understanding of my invention.

In the present instance I have shown my 70 invention embodied in a No. 11 Remington machine in which devices of my invention in the nature of attachments may be readily incorporated without modifying, or materially modifying, the structural features of said machine as they now exist. By this embodiment of my invention I am enabled to 75 convert the ordinary tabulator of the Gorin type, and in which denominational positions in successive columns may be selected, into a tabulator in which column selection, or combined column and denominational selection 80 at a single run of the carriage, may be effected. While I have shown my invention included in a No. 11 Remington machine with the results stated, it should be understood 85 that the invention may be embodied in other styles of machines.

From certain aspects there are features of the present invention which are similar to 90 some of those disclosed in an application, Serial No. 12,511 filed by me March 6, 1915, and there are claims in said previously filed application which cover the present construction. The claims in this case are 95 restricted to features not disclosed in the earlier filed application.

The frame of the machine comprises a base 1, corner posts 2 and a top plate 3. A carriage comprising end bars 4, a rear cross bar 5 and a front cross bar 6, is mounted 100 for movement from side to side of the machine over the top plate. Thus the front cross bar 6 of the carriage is grooved at 7 to receive anti-friction balls or rollers 8 which are likewise received in an oppositely 105 grooved fixed guide rail 9. The rear cross bar 5 of the carriage is grooved at 10 to receive anti-friction balls or rollers 11 which are likewise received in an oppositely grooved fixed guide rail 12. A cylindrical platen 110

13 is carried by the carriage and upwardly and rearwardly striking type bars 14 impact against the front face of the platen. A spring drum 15 is connected by a band 16 to a bracket 17 secured to the carriage at the right-hand end thereof. This drum propels the carriage from right to left under control of the usual step-by-step or letter feed mechanism, and also propels the carriage when it is released from the control of its escapement mechanism, as for example, when the tabulator mechanism is actuated. A feed rack 18 is carried by arms 19 pivoted at 20 to the rear cross bar 5 of the carriage. The feed rack engages a feed pinion 21 secured to the forward end of an escapement wheel shaft which turns in a fixed bearing 22 secured to the top plate of the machine. The rear end of the escapement wheel shaft carries a double escapement wheel 23 which co-acts with the key controlled escapement dog in the usual manner. A shoe 24 extends beneath the feed rack 18 and is carried by a release lever 25 pivoted at 26 to a bracket on the top plate of the machine. The rear end of the release lever is connected to a downwardly extending link 27, which latter is connected at its lower end to an arm 28 fixed to a rock shaft 29 which is pivoted at 30 its ends in the base of the machine. This rock shaft carries depending crank arms 30 which are connected to links 31. The forward ends of these links are connected to ears 32 on depending arms 33 which carry a universal release bar and which are supported on a rock shaft 34. It will be understood that an actuation of the universal release bar on the operation of the tabulator is effective to transmit movement through the links 31, crank arms 30, arms 28, link 27 and release lever 25 to effect a lifting of the rack from engagement with the feed pinion 21, thus releasing the carriage from control of the escapement mechanism. Springs 30^a return the carriage releasing devices to normal position.

Rearwardly extending bracket arms 35 are secured to the rear cross bar 5 of the carriage and support at their rear ends a column stop bar 36. This column stop bar is provided with teeth on opposite sides thereof for the reception of plate-like bifurcated column stops in the interdental spaces in said bar. Denominational stops 37 are formed on the upper forwardly projecting ends of denominational stop levers 38 which are pivoted at 39 to a tabulator frame 40 secured to the frame of the machine by screws 41. The denominational stops are spaced apart at letter space intervals in the usual manner, and are adapted to be projected into the path of column stops carried by the column stop bar. Thus the lower ends of the denominational stop levers 38 are connected to push rods 42 which extend for-

wardly to the front of the machine where they are provided with tabulator keys 43. These rods extend through bearing openings in a guide member 44 secured by screws 45 to the base of the machine at the front thereof. Contractile springs 46 are connected at their forward ends to a member 47 secured to the guide member 44. The rear ends of said springs are secured to their respective push rods by screws 48. These screws are received in tapped openings in collars 49 and are adapted to bear at their inner ends against the push rods in order to secure the collars in the positions to which they may be adjusted along the push rods. Adjustable collars or contact devices 50 are likewise adjustably secured on the stop rods by set screws 51 and are adapted to coact with the universal release bar to effect a rearward movement of the same and thereby operate the carriage releasing means to lift the feed rack and release the carriage from control of its escapement mechanism. The guide member 44 is provided on its upper inclined face with denominational indices 52 which are in register with the respective tabulator keys 43 which they are intended to designate.

The parts as thus far described, constitute part of the ordinary equipment of the No. 11 Remington machine and further description thereof is deemed unnecessary.

In the No. 11 Remington machine the denominational stops are always projected forwardly the same distance in the path of the column stops. By my present invention I provide regulating means whereby all of the denominational stops may be projected a uniform distance at one time and a uniform distance of a different extent at another time. In this manner the denominational stops may be brought into co-operation with column stops which project variable distances from the column stop bar, and thus bring about an arrest of the carriage after a single run at any desired column and at any desired denominational position within the selected column. I also provide means whereby the carriage release mechanism may be variably effected in accordance with the variation in the throw of the denominational stops.

The arresting means referred to above consist, in the present instance, of a plurality of stops or arresting bars or members 53, 54, 55, 56. The bar 53 is fixed by screws 57 to bracket arms 58, which latter in turn are secured by screws 59 to a part 60 fixed to the base of the machine. The arresting bar 53 is slotted at 61 for the free passage therethrough of the actuating devices or tabulator push rods 42, and likewise for the free passage therethrough of auxiliary push rods or actuating devices 62, 63, 64 and 65. There may be any suitable number of these aux-

iliary push rods in accordance with the number of columns to be selected. In the present instance I have shown four such push rods, each provided with a key 66 arranged beneath one of the tabulator keys 43. Contractile springs 67 are connected at their forward ends to a supplemental plate 68 which is secured to the usual guide 44. The rear end of each spring is connected to the associated auxiliary push rod by means of a screw 69. From an inspection of Figs. 1, 4 and 6 it will be observed that these push rods 62, 63, 64 and 65 are arranged from left to right beginning beneath the left-hand end of the series of push rods 42 so that each key 66 is arranged directly beneath a key 43. Moreover, it will be observed that each of the push rods 63, 64 and 65 is provided with an upwardly projecting cam 70 formed with an inclined face 71 and a dwell 72. It will likewise be observed that the rod 62 is devoid of any such cam. These rods pass freely through openings 61 in the member 53 and through the openings 73 in the various arresting members or bars 54, 55 and 56. Each of said arresting bars, with the exception of the fixed bar 53, is supported for vertical movement by a pair of links 74, each link extending outwardly from an end portion 30 of the associated arresting bar. Each link 74 is pivoted on a shouldered pivot screw 75 to the body portion of its associated arresting bar. The opposite end of each link is pivoted to turn on the axis of a shouldered pivot screw 76 threaded into the link and turning freely in a bearing opening in an arm 77 of a bracket 78. These brackets are secured by screws 79 to the forward face of the fixed arresting bar or member 53. The arms 77 on each bracket have a stepped shape arrangement, as indicated in Fig. 4 in order to bring them into different planes substantially coincident with the planes of the associated arresting bars which are supported thereby 45 through the intermediate links. It will be understood that there is sufficient lost motion at the points of pivotal connection of the links to prevent a buckling of the parts, thus enabling the movable arresting bars to 50 be freely elevated to their operative positions, as will hereinafter more clearly appear. From an inspection more particularly of Fig. 6, it will be seen that each cam 70 is coöperative with one of the arresting members or bars to lift it to operative position and is ineffective on the other bars. For example, the cam 70 on the push rod 63 is aligned with openings 80 in the first two of the arresting bars 55 and 56, whereas, there 55 is a closed portion 81 at a corresponding point on the arresting member 54 which stands in the path of the cam. As the cam is moved rearwardly it will pass freely through the openings 80 in the first two arresting 60 plates and co-act with the closed portion 81

of the member 54 to elevate this member to the operative position. On the other hand, the members 54 and 56 have openings 80 aligned with the cam on the push rod 54, whereas the member 55 has a closed portion 70 65 81 with which said cam is adapted to be brought into coöperation to elevate the arresting member 55. The cam on the push rod 65 co-acts with a closed portion 81 on the member 56 to lift this first of the arresting members, the second and third members 55 and 54 respectively being provided with slots 80 to permit the cam to pass freely therethrough. The last arresting bar 53 is, as before pointed out, slotted at 61 so that 80 all of the cams 70 may pass freely through or into said slots.

In Fig. 5 I have illustrated the push rod 64 in the actuated position, thus effecting an elevation of the arresting member 55 and 85 allowing the arresting members 54 and 56 to remain in the lowermost or normal position. From an inspection of this figure it will be understood that a movement of the push rod 64 to its operative position, as indicated in this figure, is effective to elevate the arresting member 55 and bring it into the path of all of the collars or stops 49 on the push rods 42, thereby arresting the rearward movement of any or all of said push rods and the denominational stops 37 controlled thereby. The effect of the arresting mechanism described is, as stated, to limit the extents of forward movement of the denominational stops and thus bring them into 90 the paths of different column stops. Thus I have shown, in the present instance, four column stops 82, 83, 84, 85 which project rearwardly different distances from the column stop bar 36. The finger keys 66 on the push rods 62, 63, 64 and 65 may be numbered progressively from left to right on the heads thereof "1," "2," "3," and "4." As heretofore explained the push rod 62 is devoid of a cam 70 so that the actuation of this push rod is ineffective on any of the arresting bars or members. This being the case, the tabulator keys 43 may be moved rearwardly their greatest extent, or until they are arrested by the collars or stops 49 100 co-acting with the fixed arresting bar or member 53. This is effective to project the actuated denominational stop into the path of the shortest column stop 82 arranged at the left-hand end of the series, thereby arresting the carriage at the first columnar field, and in the desired denominational position within this field as determined by the particular tabulator key 43 which has been actuated. Should the operator desire to arrest the carriage at, say, the hundreds position in the fourth column, it is merely necessary to first push rearwardly the key bearing the index numeral 4, thus elevating the arresting bar 110 56 which is farthest forward and bringing 120 125 130

it into the path of the stops 49 on the tabulator push rods. The operator may then push the hundreds key rearwardly, projecting the corresponding denominational stop 5 into the path of the fourth column stop 85, counting from left to right, and the carriage will be arrested after a single run in the fourth columnar field and in the hundreds position within that field. Should the operator desire merely to column select, the desired selecting key 66, say, the one bearing the index numeral "3," should be pushed rearwardly, then an actuation of the last of the series of tabulator keys 43 opposite the 15 "1,000,000" point will be effective to release the carriage and bring about an arrest thereof for writing within the third columnar field. Where wide columns are used and it is desired merely to column select 20 and to bring about an arrest of the carriage so as to begin writing near the left-hand side of each column on the paper, the operation would be as follows:—Each column stop is set so as to begin a column when the decimal stop 25 coacts therewith, the proper selecting key 66 is actuated and then the decimal key is operated. Thus, should the operator desire to begin writing in the third column beginning at, say, "45" on the scale, the column stop 30 having been set at "45" on the stop rod, an actuation of the column selecting key 66 bearing the index numeral "3" will be effected and the decimal key will then be operated. This will bring about an arrest so as to begin writing at the first part 35 of the third column.

It will be observed that each of the arresting members 54, 55 and 56 is provided with notches or recesses 86, each arranged 40 beneath one of the tabulator push rods 42. This is in order that the collars or stops 49 may be brought into effective engagement with the arresting members when the latter are elevated to the arresting position, as indicated in Fig. 5. In order to provide an effective bearing for the arresting plates, one against another, when they are in the elevated positions, and to prevent a teetering of the plates through the pressure of the 45 contact devices 50 thereon, I preferably provide upwardly extending lugs 87 on the plates 54 and 55, these lugs being of the same thickness as the plates themselves. Thus, the lugs 87 on the plate 54 will constitute a bearing for the plate 55 when the latter is in the elevated position, and will resist a rearward pressure on said plate at a height which corresponds substantially to the height of the contact devices 49. On 50 the other hand, the lugs 87 on the plate 55 will resist a rearward pressure exerted against the plate or arresting member 56. It will be understood, of course, that ultimately the rearward pressure exerted by 55 the contact devices or stops 49 is resisted by

the fixed arresting member 53. I have eliminated these bearing lugs 87 in Figs. 1 and 5 to avoid confusion in the showing. It will be understood, moreover, that in Fig. 4 the first four tabulator keys 43, counting from 70 left to right, together with the forward end portions of the push rods which carry them, have been omitted in order to disclose the selecting key 66 and the push rods 62, 63, 64 and 65 which are arranged beneath the 75 first mentioned push rod and keys. The movable arresting members 54, 55 and 56 may be supported in the normal position by supporting pins 88 which project forwardly from the fixed arresting bar or member 53 80 and may be received in cut-outs or apertures 89 in the movable arresting members.

In the No. 11 Remington machine the collars 50 on the tabulator push rods constitute contact devices which co-act directly with a 85 universal release bar 90 to effect an operation of the carriage releasing means when a tabulator key is actuated to project a denominational stop forward to operative position. In the present instance I have provided means whereby a variation in the timing of the release with reference to the operation of the tabulator push rod may be effected. These means correspond in construction to the arresting members 53, 54, 55 90 and 56 except that they are mounted on and movable with the universal bar instead of being carried by a fixed part of the machine, as is the case with the arresting means. Thus, I have provided three members 91, 92, 100 93 which I term interponents and which, as hereinbefore stated, are constructed and mounted like the arresting members with which the stops 49 co-act. These interponents are mounted on links 94 which, like 105 the links 74, are pivoted on brackets 95 secured in this instance to the universal release bar 90 and movable bodily therewith in the movement of the latter around the pivotal axis of the rock shaft 34. Cams 96 are provided on the push rods 63, 64 and 65 which co-act with the interponents to elevate them into the paths of the contact devices 50 on the push rods of the tabulator keys. The operation of the cams 96 on the interponents is similar to the operation of the cams 70 on the arresting members. Thus the cam 96 carried by the push rod 63 is effective to elevate the rear interponent 91 and bring it into the path of the contact devices 50 on the tabulator push rods 42, whereas an actuation of the push rod 64 is effective to elevate the second interponent 92 and bring it into the path of the contact devices 50. An actuation of the fourth column selecting key 110 to move the push rod 65 rearwardly is effective to elevate the first interponent 93 and bring it into the path of the contact devices 50. On the other hand, an operation 115 of the first selecting key carried by the push 120 rods 62 and 66 is effective to move the interponent 94 forwardly and bring it into the path of the contact devices 50. The cam 96 carried by the push rod 65 is effective to move the interponent 94 rearwardly and bring it into the path of the contact devices 50. An actuation of the second selecting key 125 carried by the push rod 66 is effective to move the interponent 94 forwardly and bring it into the path of the contact devices 50. The cam 96 carried by the push rod 62 is effective to move the interponent 94 rearwardly and bring it into the path of the contact devices 50. An actuation of the third selecting key 130 carried by the push rod 63 is effective to move the interponent 94 forwardly and bring it into the path of the contact devices 50. The cam 96 carried by the push rod 64 is effective to move the interponent 94 rearwardly and bring it into the path of the contact devices 50.

rod 62 will have no effect on the interponents, and an operation of a tabulator key for the fullest extent of its movement may be brought about, and the associated contact device 50 will be brought into coöperation with the body portion of the universal bar 90. This operation of the universal bar through the intermediate train of connections elevates the feed rack 18 in order to release the carriage. The operation of the interponents to correspond with the particular arresting member which is elevated is illustrated in Fig. 5. From this figure it will be seen that an actuation of the selecting key on the push rod 64 is effective to elevate the second arresting member 55 and the second interponent 92. This view illustrates the parts as they appear after the selecting key on the push rod 64 has been actuated, and after one of the denominational keys has been actuated. It will be seen that the tabulator key and the parts controlled thereby have been arrested and that the universal release bar has been operated to release the carriage from control of the escapement mechanism while the corresponding denominational stop has been projected into the path of the column stop 84, this latter being determined by the particular selecting key which has been operated.

From the foregoing description it will be understood that the universal release bar will be taken up and actuated sooner or later in the strokes of the tabulator keys, depending on the extent of movements which may be given said keys as determined by the arresting means. In this manner I have provided means for automatically varying the release of the carriage in accordance with the variation in the throw of the denominational stops, in order that the carriage may be properly released irrespective of the extent of throw given to the denominational stops. If for example a denominational stop receives its greatest extent of throw to bring it into the path of the column stop 82, then the carriage will not be released until the last portion of the movement of said denominational stop, and through the coöperation of the contact device 50 directly with the universal release bar 90. On the other hand, if a denominational stop should receive its shortest extent of movement to bring it into the path of the column stop 85, then the associated contact device 50 will co-act with the interponent 93 and start to move the universal release bar at the first part of the movement of the tabulator key, thus effecting a release of the carriage by the time the projected denominational stop is in the path of the column stop 85.

Of course, it will be understood that by actuating the tabulator keys 43 in the ordinary manner without a prior actuation of

the selecting keys, denominational selection in successive columns will be effected in the usual manner. At this time the denominational stops would receive their greatest extent of throw, and would be brought into co-operation with any of the column stops 82, 83, 84 or 85 and no columnar selection would be effected. Moreover, it will be understood that the release of the carriage would be properly timed for the use of the tabulator in this manner. It will also be understood that in these circumstances any number of column stops may be employed.

In order to facilitate the employment of a large number of column stops, if desired, for ordinary work at one time and to provide for the use of a comparatively restricted number of column stops 82, 83, 84 and 85 of varying lengths for column selection at another time, I have provided a column stop bar which is adapted to be turned to bring either one or another of two sets of column stops into use, as is sometimes provided in the No. 11 Remington machine. In the present construction the column stop bar has bearing portions 97 at the ends thereof which are received in the bearings 98 in the supporting arms 35 for the column stop bar. One of these bearing portions is flattened on opposite faces thereof, as indicated at 99, for coöperation with a flattened end of a spring pressed pin or detent 100. This detent may be connected by a rivet, or otherwise, to a spring 101 secured at one end by a screw 102 to the associated bracket arm 35. The pressure of the spring detent is exerted to retain the column stop bar in either of the two positions to which it may be rotated in its bearings to bring either the column stops 82, 83, 84, 85 or the column stops 103, which project from the opposite side of the bar, into use. One end of the column stop bar extends beyond its bearing and is reduced at 104 (see Fig. 4) to receive a knurled finger piece 105 secured to the stop bar by a nut 106.

While in the present instance I have shown the machine equipped for the selection of four columns, it should be understood that this number may be increased if desired by the provision of additional selecting keys 66, interponents and arresting devices and by dividing the full extent of throw of the denominational stops into a greater number of extents, one extent of movement being provided for each arresting device and interponent and selecting key employed. In such a case, of course, the thickness of the arresting members and interponents, as well as the extent of overlap of a denominational stop with each of the column stops, will be decreased. Then again, without modifying the structure, one or more additional sets of column stops 82, 83, 84, 85 may be employed, one set, say, for

affording a selection of any one of the first four columns in the first half of the run of the carriage, and a second set for affording a selection of any one of four columns during the second half of the run of the carriage. In this manner or in the manner previously described, the selecting mechanism may be employed for the selection of a larger number of columns than is shown 10 in the present instance, though for ordinary work the selection of any one of four columns has been found to be sufficient in practice.

It will be seen that I have provided simple and comparatively inexpensive devices, which are in the nature of attachments, that may be readily embodied in existing machines without modifying, or materially modifying, the structural features thereof, 20 and with the aid of which ordinary tabulator mechanism of the Gorin type may be readily converted into a combined column and denominational selector, for effecting an arrest of the carriage at any desired columnar field and at any desired denominational position within the selected field after a single run of the carriage. It will also be understood that, when desired, this tabulator mechanism may be used in the 30 ordinary manner of a Gorin tabulator to effect denominational selections in successive columns or may, when desired, be used merely as a column selector.

While I have shown and described with considerable particularity one form of construction embodying my invention I am aware that various changes may be made without departing from the spirit and scope of my invention.

40 What I claim as new and desire to secure by Letters Patent, is:—

1. In a typewriting machine, the combination of a carriage; and tabulator mechanism comprising a series of movable tabulator stops all having a uniform throw of a given extent at one time and a uniform throw of a different extent at another time, a series of tabulator keys for said stops, and controlling means operable at will to regulate 45 the extent of uniform throw that said stops may receive, said controlling means comprising a plurality of individually operable arresting members, and a separate key for each of said members.

55 2. In a typewriting machine, the combination of a carriage; and tabulator mechanism comprising a series of movable tabulator stops all having a uniform throw of a given extent at one time and a uniform throw of a different extent at another time, a series of tabulator keys for said stops, controlling means operable at will to regulate the extent of uniform throw that said stops may receive, and carriage releasing means variably actuated in accordance with the variation

in the throw of said stops, said releasing means including a plurality of interponents, and means for moving said interponents individually into operative position.

3. In a typewriting machine, the combination of a carriage; and tabulator mechanism comprising a series of movable tabulator stops all having a uniform throw of a given extent at one time and a uniform throw of a different extent at another time, a series of key controlled push rods which control said stops, limiting stops on said push rods, arresting means which co-act with the limiting stops on said push rods, and key controlled means for regulating said arresting means and thereby determining the different extents of movement that may be given to said tabulator stops.

4. In a typewriting machine, the combination of a carriage; and tabulator mechanism comprising a series of movable tabulator stops all having a uniform throw of a given extent at one time and a uniform throw of a different extent at another time, a series of key controlled push rods which control said stops, limiting stops on said push rods, arresting means which co-act with the limiting stops on said push rods, key controlled means for regulating said arresting means and thereby determining the different extents of movement that may be given to said tabulator stops, and carriage releasing means actuated by said push rods variably in accordance with the variation in the throw of said tabulator stops, said carriage releasing means comprising a plurality of interponents, and key controlled means for moving said interponents individually into co-operative relation with said push rods.

5. In a typewriting machine, the combination of a carriage; and tabulator mechanism comprising column stops, a series of movable selecting stops all having a uniform throw of a given extent at one time and uniform throw of a different extent at another time, a series of key controlled push rods which control said selecting stops, limiting stops on said push rods, a plurality of arresting bars co-operative with said limiting stops to control the extent of throw that may be given the selecting stops, and key controlled means for controlling said arresting bars.

6. In a typewriting machine, the combination of a carriage; and tabulator mechanism comprising column stops, a series of movable selecting stops all having a uniform throw of a given extent at one time and a uniform throw of a different extent at another time, a series of key controlled push rods which control said selecting stops, limiting stops on said push rods, a plurality of arresting bars co-operative with said limiting stops to control the extent of throw that may be given the selecting stops, key controlled means for controlling said arresting bars,

and carriage releasing means including means whereby a variable release of the carriage may be effected in accordance with the variation in the throw of the selecting stops.

5 7. In a typewriting machine, the combination of a carriage; and tabulator mechanism comprising column stops, a series of movable selecting stops all having a uniform throw of a given extent at one time and a uniform throw of a different extent at another time, a series of key controlled push rods which control said selecting stops, limiting stops on said push rods, a plurality of arresting bars coöperative with said limiting stops to control the extent of throw that may be given the selecting stops, key controlled means for controlling said arresting bars, and carriage releasing means including a universal release bar controlled by said push rods, a plurality of bars adapted to be interposed operatively between said push rods and said universal bar, and means under control of said controlling means for interposing said last mentioned bars as specified.

8. In a typewriting machine, the combination of a carriage; and tabulator mechanism comprising column stops, a series of movable selecting stops all having a uniform throw of a given extent at one time and a uniform throw of a different extent at another time, a series of key controlled push rods which control said selecting stops, adjustable limiting stops on said push rods, a plurality of arresting bars coöperative with said limiting stops to control the extent of throw that may be given the selecting stops, key controlled means for controlling said arresting bars, and carriage releasing means including a universal release bar, adjustable contacts on said push rods, a plurality of bars adapted to be interposed between said contacts and said universal bar, and means under control of said controlling means for selectively interposing said last mentioned bars as specified in accordance with the arresting bar which is in use.

9. In a typewriting machine, the combination of a carriage; and tabulator mechanism comprising column stops, a series of movable selecting stops all having a uniform throw of a given extent at one time and a uniform throw of a different extent at another time, a series of key controlled push rods which control said selecting stops, limiting stops on said push rods, a plurality of arresting bars coöperative with said limiting stops to control the extent of throw that may be given the selecting stops, and a plurality of keys each operative on one only of said arresting bars to control it in its movement into and out of operative position.

10. In a typewriting machine, the combination of a carriage; and tabulator mecha-

nism comprising column stops, a series of movable selecting stops all having a uniform throw of a given extent at one time and a uniform throw of a different extent at another time, key actuated devices for controlling said selecting stops, a plurality of independently operable arresting devices each coöperative with all of said key actuated devices, and keys each operative on a given one only of said arresting devices to move it into operative position.

11. In a typewriting machine, the combination of a carriage; and tabulator mechanism comprising column stops, a series of movable selecting stops all having a uniform throw of a given extent at one time and a uniform throw of a different extent at another time, key actuated devices for controlling said selecting stops, a plurality of independently operable arresting devices each coöperative with all of said key actuated devices, keys each operative on a given one only of said arresting devices to move it into operative position, and carriage releasing means actuated variably in accordance with the extent of throw of said selecting stops, said releasing means including a plurality of individually movable interponents, and means controlled by said keys for moving said interponents into operative position.

12. In a typewriting machine, the combination of a carriage; and tabulator mechanism comprising column stops, a series of movable selecting stops all having a uniform throw of a given extent at one time and a uniform throw of a different extent at another time, key actuated devices for controlling said selecting stops, a plurality of independently operable arresting devices each operative with all of said key actuated devices, and key controlled push rods each carrying a cam operative on one only of said arresting devices to move it into operative position.

13. In a typewriting machine, the combination of a carriage; and tabulator mechanism comprising column stops, a series of movable selecting stops all having a uniform throw of a given extent at one time and a uniform throw of a different extent at another time, key actuated devices for controlling said selecting stops, a plurality of independently operable arresting devices each operative with all of said key actuated devices, key controlled push rods each carrying a cam operative on one only of said arresting devices to move it into operative position, and carriage releasing means actuated variably in accordance with the extent of throw of said selecting stops, said releasing means including a plurality of individually movable interponents, and cams on said key controlled push rods each operative on one only of said interponents to move it into operative position.

14. In a typewriting machine, the combination of a carriage; and tabulator mechanism comprising column stops, a series of movable selecting stops all having a uniform throw of a given extent at one time and a uniform throw of a different extent at another time, key actuated devices for controlling said selecting stops, a plurality of independently operable arresting devices each coöoperative with all of said key actuated devices, key controlled push rods each carrying a cam operative on one only of said arresting devices to move it into operative position, and carriage releasing means actuated variably in accordance with the extent of throw of said selecting stops, said releasing means including a universal release bar controlled by said key actuated devices, contact bars carried by said universal bar and movable individually into and out of the paths of said key actuated devices, and cams on said push rods and each coöoperative with one only of said contact bars to move it into the path of said key actuated devices.
15. In a typewriting machine, the combination of a carriage; and tabulator mechanism comprising a series of movable tabulator stops all having a uniform throw of a

given extent at one time and a uniform throw of a different extent at another time, 30 a series of key controlled push rods which control said stops, limiting stops on said push rods, arresting means which co-act with the limiting stops on said push rods, key controlled means for regulating said arresting means and thereby determining the different extents of movement that may be given to said tabulator stops, and carriage releasing means actuated by said push rods 40 variably in accordance with the variation in the throw of said tabulator stops, said carriage releasing means comprising means whereby the releasing means will be taken up earlier or later in the throw of the push rods and the timing of the release be made 45 to accord with the extent of throw of the push rod.

Signed at the borough of Manhattan, city of New York, in the county of New York, and State of New York, this 3rd day of May A. D. 1915.

CHARLES E. SMITH.
